Her Attorney, Esq.

UNITED STATES PATENT OFFICE

VIOLA F. KONCEN, OF CLAYTON, MISSOURI

SLIP

Application filed February 11, 1929. Serial No. 338,983.

This invention relates to a slip, an article of ladies' wear, a garment which is suspended only from the shoulders of the wearer and is loosely suspended about the body of the wearer.

An object of the invention is to provide a ladies' slip constructed at the upper end to fit better around the chest and below the arms and having a fullness at the front and a narrowed portion at the waist and provided with pleats at the lower skirt portion permitting the garment to be worn with ease and comfort.

Another object of the invention is to provide a slip of novel construction at the waist and at the upper end so as to obtain proper fit around the upper end and a fullness above the waist and being capable of flaring at the lower end.

Another object of the invention is to provide an improved slip of the character and type mentioned having spaced darts at the upper end of the front and at the front of the connection of the waist with the skirt and having darts extending from about the connection of the waist with the skirt upwardly to the upper end of the waist at the sides leaving a fullness of the waist at the front and obtaining a comparatively snug fit of the upper end of the garment on the wearer.

Another object of the invention is to provide a slip of the character and type last above mentioned having a skirt that is capable of being flared or enlarged so that the garment may be worn easily.

Other objects will appear from the following description, reference being made to the accompanying drawings in which

Fig. 1 is a front elevation of a preferred embodiment of the invention.

Fig. 2 is a rear elevation.

Fig. 3 is a diagrammatical view representing a section taken on the line 3—3 of Fig. 1.

Fig. 4 is a diagrammatical view representing a section taken on the line 4—4 of Fig. 2.

Fig. 5 is a diagrammatical view representing a section taken on the line 5—5 of Fig. 1.

Fig. 6 is a diagrammatical view represent-

ing a section taken on the line 6—6 of Fig. 1.

Fig. 7 is a view showing the inside of the front of the garment.

Fig. 8 is a view showing the inside of the rear of the garment.

Fig. 9 is a front elevation showing a modified construction and arrangement at the connection of the waist with the upper end of the skirt.

Fig. 10 is a rear elevation of the modified type of garment shown in Fig. 9.

In the specific embodiment of the invention shown in the drawings the body of the garment is made or composed of two sections or panels of fabric, although it will be apparent that the garment may be varied in this respect if desired. There is a front panel 1 and a rear panel 2 of approximately the same vertical length. These panels are of different horizontal width, the front panel 1 being much wider than the rear panel 2. The panel 1 is folded, as shown in Fig. 4, so as to provide a skirt portion for the garment in which the vertical edges of the front panel 1 extend around to the rear but are spaced apart and in which the vertical edges of the rear panel 2 are folded inwardly to provide plaits 3 for the skirt so as to permit the skirt to be opened to larger extent when worn. The panel 1 and the panel 2 are folded in this manner throughout their vertical length and their marginal portions are arranged one against the other and sewed together through the length of the garment by rows of stitches 4.

The front panel 1 is folded inwardly on a line 5 beginning at its marginal edges to provide downwardly and forwardly tapered tucks 6 made permanent by a line of stitches along the line 5 so as to shorten the outer edges of the garment. The lines of stitches 4 cross the wider ends of the tucks 6 and strengthen the construction. Below the rear ends of the tucks 6 a continuous line of stitches 7 extend upwardly from the lower marginal edge parallel with the line of stitches 4 and are continued by lateral lines of stitches 8 a few inches below the rear ends of the tucks 6 and extending laterally to the lines of stitches 9. The edges of the upper

ends of the plaits 3 from the ends of the lateral rows of stitches 8 are sewed to the front panel 1 by the lines of stitches 9 which extend to the upper end of said front panel 1. That is to say, the upper ends of the plaits 3 are sewed to the front panel 1 against which said plaits 3 lie by the vertical rows of stitches 9 running from a few inches below the tucks 6, crossing said tucks and extending to the upper end of the garment. By this construction the plaits 3 are permitted to flare and unfold below the stitching 8 but are held from flaring or unfolding from the ends of the lines of stitches 8 to the upper end of the garment.

The waist portion of the front panel 1 is folded at each side to provide a dart 10 extending from the line 5 to the upper end of the garment so as to make the upper end of the garment of reduced size and provide for closer fit of the garment around the waist of the wearer. And the upper end of the front of the panel 1 is folded to form two short darts 11, further reducing the size of the upper end of the garment and leaving the front 12 of the garment between the upper edge and the lines 5 loosely plaited or ruffled in order to fit the waist.

Straps 13 having their ends attached to the upper end of the front and rear of the garment, respectively, are provided to engage over the shoulders of the wearer in order to support the garment. Preferably the front ends of these straps are attached to the darts 11. The darts 11 are maintained by lines of stitches 14. Below the darts 11 the front panel of the garment is folded to provide two spaced plaits 15 each being sewed by a rectangular frame of stitches 16 lapping the plaits above and below said frames of stitches far enough to open or spread in conformity with the body of the wearer in order to fit properly.

The variation shown in Figs. 9 and 10 consists in running a line of stitches 17 entirely across the inner and outer folds of the back panel 2 forming the plaits 3 and also through that portion of the marginal edges of the front panel 1 which are overlapped by the plaits 3 and thence entirely across the rear panel 2. This modification of Figs. 9 and 10 further differs from the construction previously described by forming vertical tucks 18 held by the lines of stitches 5. These vertical tucks 18 extend only above the lines of stitches 5 and do not extend below as do the plaits 15. To other parts of the garment shown in Figs. 9 and 10 the same reference numerals are applied to indicate structural features previously described.

From the foregoing it must be apparent that I have provided an improved garment that will fit to the form of the wearer better than other garments which do not include the features of construction herein shown and described, and which, while fitting more

closely around the upper portion of the waist, will not interfere with the ease and comfort with which the garment may be worn. Further, the lines of stitches run on nearly straight lines and the folds, tucks, darts and plaits are provided and made where they may be conveniently formed so that the entire result of the completion of the garment is an attractive article of apparel without complicated or costly features of construction. I contemplate such variations as may be made without departure from the nature and principle of the invention.

What I claim and desire to secure by Letters Patent is:—

1. A slip comprising a front panel having its vertical lateral portions extended inwardly to form the laterally spaced rear portions of the slip, a rear panel having its vertical lateral portions folded inwardly and forming plaits against said rear lateral portions of the front panel, said panels being secured together throughout their length by stitches adjacent to the vertical edges of said panels, stitches connecting said plaits with the adjacent inwardly extended portions of the front panel laterally from said stitches which are adjacent to the edges of said panel and extending approximately the upper half of the vertical length of the slip, leaving the plaits of the rear panel below said stitches detached from the front panel other than along its edges, fold tucks at the sides of the waist-line of the front panel and tapering forwardly to discontinuance, and darts formed near the upper end of the front panel reducing the size of the slip near its upper end.

2. A slip comprising a front panel having its vertical lateral portions extended inwardly to form the laterally spaced rear portions of the slip, a rear panel having its vertical lateral portions folded inwardly and forming plaits against said rear lateral portions of the front panel, said panels being secured together throughout their length by stitches adjacent to the vertical edges of said panels, stitches connecting said plaits with the adjacent inwardly extended portions of the front panel laterally from said stitches which are adjacent to the edges of said panel and extending approximately the upper half of the vertical length of the slip, leaving the plaits of the rear panel below said stitches detached from the front panel other than along its edges, darts formed near the upper end of the front panel reducing the size of the slip near its upper end, and approximately horizontal tucks extending from the rear edges of the front panel across the lower ends of said darts and tapering to discontinuance near the front of the front panel.

3. A slip comprising a front panel having its vertical lateral portions extended inward-

ly to form the laterally spaced rear portions of the slip, a rear panel having its vertical lateral portions folded inwardly and forming plaits against said rear lateral portions of the front panel, said panels being secured together throughout their length by stitches adjacent to the vertical edges of said panels, stitches connecting said plaits with the adjacent inwardly extended portions of the front panel laterally from said stitches which are adjacent to the edges of said panel and extending approximately the upper half of the vertical length of the slip, leaving the plaits of the rear panel below said stitches detached from the front panel other than along its edges, darts formed near the upper end of the front panel reducing the size of the slip near its upper end, approximately horizontal tucks extending from the rear edges of the front panel and tapering to discontinuance near the front of the front panel, and means holding portions of the front panel folded upon themselves for a distance above the forward portions of said tucks, leaving a fullness at the front of the slip above said folded portions and below the planes of said darts.

4. A lady's slip comprising a front panel and a rear panel having their vertical lateral portions extended inwardly to form the laterally spaced rear portions of the slip and secured together along their vertical edges, the inwardly extended portions of said rear panel forming plaits, stitches securing said plaits to the inwardly extended portions of the front panel from near the waist-line of the slip to near the upper edge of the slip, leaving the plaits of the rear panel from the waist downwardly disconnected from the front panel other than by the stitches near the edges of said panels and for approximately the length of the skirt of the slip, darts formed in the sides of the front panel near its upper end reducing the size of the upper end of the slip from about the waistline upwardly, and stitched folds formed at the waistline and in the front panel and intermediate the lower ends of said darts and reducing the size of the waistline of the slip.

5. A lady's slip comprising a front panel and a rear panel having their vertical lateral portions extended inwardly to form the laterally spaced rear portions of the slip and secured together along their vertical edges, the inwardly extended portions of said rear panel forming plaits, stitches securing said plaits to the inwardly extended portion of the front panel from near the waist-line of the slip to near the upper edge of the slip, leaving the plaits of the rear panel from the waist downwardly disconnected from the front panel other than by the stitches near the edges of said panels and for approximately the length of the skirt of the slip, darts formed in the front panel near its upper end reducing the size of the upper end of

the slip from about the waistline upwardly, approximately horizontal tucks formed in the front panel from the rear edges and tapering forwardly to the front ends of said tucks which terminate in spaced relationship, and means holding portions of the front panel overlapped near the ends of said tucks and leaving portions of the front panel unrestricted above said overlapped portions to the planes of said darts.

6. A slip comprising a front panel of a width to extend to the rear of the wearer, a rear panel having its vertical lateral portions folded inwardly and forming plaits against the rear lateral portions of the front panel, said panels being secured together along their vertical edges, means securing said plaits to adjacent rear lateral portions of the front panel above the waist-line to provide three plies of material for the rear of the slip above the waist-line, vertical darts at the sides of the front panel extending from the waistline upwardly, approximately horizontal tucks extending across the sides of the front panel and tapering to discontinuance near the front of the front panel, plaits formed adjacent to the forward ends of said tucks, and darts formed at the upper end of the front panel between said first named darts.

7. A slip comprising a front panel having its vertical lateral portions extended to the rear of the wearer, a rear panel having its vertical lateral portions folded inwardly and forming plaits against the rear lateral portions of the front panel, said panels being secured together throughout their length by stitches adjacent to the vertical edges of said panels, means preventing unfolding of said plaits above the waist-line of the slip, tucks at the sides of the front panel near the waistline reducing the length of the side portions of the slip, and series of pairs of stitched folds arranged in spaced relationship and reducing the size of the slip at the waist-line and at the upper end of the slip and leaving portions of the front panel unrestricted above the waist-line and below the upper end of the slip.
